UNITED STATES PATENT OFFICE

2,530,069

COMBINATION FLASHLIGHT AND TABLE LAMP

George H. Moore, Snow Hill, N. C., assignor of
one-fourth to Walter G. Sheppard, Greene
County, N. C.

Application March 2, 1949, Serial No. 79,206

1 Claim. (Cl. 240—10.64)

1

This invention relates to a novel illuminating device the primary object of which is to permit the conversion of the light alternately to a flashlight or a table lamp.

Another object of this invention is to provide a novel combination flashlight and lamp which is extremely simple in construction and design, efficient in operation, and extremely useful for its intended purposes.

A further object of this invention is to provide a device of the character described which is operated by the conventional battery, battery case and slide switch so that the device is cheap to operate and easy to assemble.

Yet another object of this invention is to provide a combination flashlight and lamp comprising a casing having a base, a battery in said casing, a reflector at the top end of said casing, a bulb carried by said reflector, a switch in said casing for energizing said bulb, a transparent globe at the top of said casing enclosing said reflector and bulb, and means for selectively shielding and exposing said globe.

These, together with various ancillary objects and features of the invention which will later become apparent as the following description proceeds, are attained by the device, a preferred embodiment of which has been illustrated by way of example only in the accompanying drawings, wherein:

Figure 1 is a front elevational view of the device shown employed as a table lamp;

Figure 2 is a view similar to that shown in Figure 1 illustrating the device employed as a flashlight; and

Figure 3 is a longitudinal sectional view through the device shown in Figure 1, parts being broken away to show details of construction.

Specific reference is now made to the drawings. In the several views in the accompanying drawings and in the following specification reference characters indicate corresponding elements throughout.

Indicated generally at 10 is a conventional battery casing. Secured to or integral with the bottom edge of the casing is an outwardly flared base 12 for supporting the device on a table top when the latter is being employed as a lamp. Within the casing 10 is positioned the conventional battery 12 and positioned within the casing and resting on top of the battery is an inverted, semi-spherical or parabolic highly polished reflector 14 having a threaded socket 16 for receiving an electric bulb 18. It will be understood that a conductor wire connects the socket 16 to

the upper terminal of the battery (not shown).

The upper end of the casing 10 is provided with a threaded edge 20 for receiving the threaded recess 22 at the bottom edge of a transparent globe 24 which may be fabricated of glass, or a transparent plastic such as "lucite." The side of the casing is further provided with the conventional slide switch 26.

To convert the device from a table lamp as shown in Figure 1 to a flashlight as shown in Figure 2, and vice versa, the following means is provided. A shield 28 is provided which is slidable on the casing 10 and has a bottom edge 30 receivable upon the upper edge 32 of the base 12 as shown clearly in Figure 3. Since the globe 24 has an external diameter equal to the external diameter of the casing 10, it will be understood that the shield 28 will be slidable on the globe 24 as well as on the casing 10.

The wall of the shield 28 is provided with an elongated slot 34 for receiving the slide switch 26 and adjacent the ends of the slot 34 the shield 28 further carries the inwardly opening recesses 36 and 38. The casing 10 is further provided with laterally extending bores 40 and 42 for receiving springs 44 and 46 urging balls 48 and 50 outwardly of the casing.

In practical operation, when the shield 28 is moved downwardly so that the bottom edge 30 engages the upper edge 32 of the base 12, the ball 48 yieldingly engages the recess 36 to retain the shield in the retracted position so that the globe 24 is exposed and the device can be employed as a table lamp. When it is desired to convert the table lamp to a flashlight, the shield 28 is moved

upwardly to the position shown in Figure 2 whereupon the ball 50 yieldingly engages the recess 38 to retain the shield 28 in the elevated position. It will be understood that the shield may be provided with an inner lining of thin polished metal to aid in the reflection of light when the shield is moved into the position shown in Figure 2.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

A combination flashlight and lamp comprising a casing having a base, a battery in said casing, a reflector at the top end of said casing, a bulb carried by said reflector, a switch in said casing for energizing said bulb, a transparent globe at the top of said casing enclosing said reflector and bulb, said globe having an external diameter equal to the external diameter of said casing, a 10 tubular shield slidable on said casing having an elongated slot receiving said switch, and means for yieldingly and selectively retaining said shield in a raised position to partially enclose said globe and in a lowered position to entirely expose said globe, said means including spring-urged balls carried by said casing on both sides of said switch and recesses adjacent both ends of said slot for selectively receiving said balls.
